UNITED STATES PATENT OFFICE

ARNOLD L. JOHNSON, OF TURLOCK, CALIFORNIA

DESIGN FOR A RADIOCABINET

Application filed January 31, 1931. Serial No. 38,506. Term of patent 14 years.

To all whom it may concern:

Be it known that I, ARNOLD L. JOHNSON, a citizen of the United States, residing at Turlock, in the county of Stanislaus and State of California, have invented a new, original, and ornamental Design for a Radiocabinet, of which the following is a specification, reference being had to the accompanying drawing, forming part thereof, which

shows perspective views of a radiocabinet showing my new design, and in which Fig. 1 is a front view of the radiocabinet, and Fig. 2 is a rear view of the same.

I claim:

The ornamental design for radiocabinets, as shown.

ARNOLD L. JOHNSON.
